UNITED STATES PATENT OFFICE.

ALBERT E. HALL, OF BOSTON, MASS., ASSIGNOR OF ONE-HALF OF HIS
RIGHT TO COURTLANDT PALMER DIXON, OF BROOKLYN, N. Y.

IMPROVEMENT IN TRANSPORTING AND DELIVERING DREDGED MATERIAL.

Specification forming part of Letters Patent No. **222,488**, dated December 9, 1879; application filed
April 11, 1879.

To all whom it may concern:

Be it known that I, ALBERT ELISHA HALL, of Boston, in the county of Suffolk and Commonwealth of Massachusetts, have invented a new and useful improvement in apparatus for removing mud or gravel from the bed of shallow waters to such locations on or near shore as it is desired to fill and raise above the flow of the tide, for wharves, buildings, or other purposes.

Heretofore such work has been done in several different ways, all tedious and slow, and in most cases involving the necessity of handling the mud or gravel twice, and sometimes oftener, and losing a portion of it at each handling.

Unloaded scows have been floated at high water to places where the mud and gravel would be left uncovered at low water, and then filled by shoveling, and again at high water floated to the place where it was desired to make the filling, or as near it as the height of water would allow, and there dumping, and, if necessary, again shoveling and moving it.

Scows have been filled with mud or gravel from the bed of shallow water, raised by a steam shovel or dredger on a hull or float, and moved as near the shore as circumstances would allow and dumped, and the mud or gravel again lifted and placed on shore on carts or cars, to be transported where the fill was to be made; but this involves two or more handlings of the filling material.

A bridge on piles has been run out from the shore to the point where the steam shovel or dredger would be located, and a rail-track laid on it, and dumping-cars run out on it to be filled, and then drawn where the filling was to be deposited; but this method was sometimes impracticable at high or low tide, and involved a double handling, or a rebuilding of the bridge as soon as the available material within reach of the dredger is removed.

My method and apparatus obviate all these objections and enable me to locate the dredger at any desirable station in a bay or arm of the sea, and remove it to any other station at pleasure, and then carry the dumping-cars, adapted to the ordinary railway-track, to it to be filled, and when filled carry them to the

landing-head, which is a part of my system, to be attached to a locomotive and drawn by it to the place where the gravel or mud is to be deposited, and there dumped, and again returned to the dredger to be refilled and landed as before, thus enabling me to raise mud or gravel from the bed of any water where it can be reached by the arm of the dredger and carry it to any point inland where I wish to deposit it, (and lay a track for a locomotive and cars to run on,) without rehandling it, or removing fixed bridges, and without regard to the height of the tide.

The invention consists in the combination and arrangement of a boat or scow of sufficient capacity to receive and carry any desirable number of dumping-cars, and so decked over as not to be liable to be filled with water and swamped, with a proper superstructure and track or tracks for the cars to move and rest on above and resting on the deck, a boat or scow properly constructed for the purpose, and covered in so that it will not be liable to be filled with water, carrying a landing-bridge with a railroad-track on it arranged to correspond with and meet the track on the boat or scow first mentioned at one end, and at the other end with a railroad-track on the landing-head on or connected with the shore, all constructed substantially as hereinafter described.

The landing-bridge is made in two equal, or nearly equal, parts or lengths, hinged to and supported by a block or structure prepared for the purpose at or near the middle of the length of the boat or scow. When in position between the scow carrying the dumping-cars and the landing-head on or approaching the shore, one end of this landing-bridge rests upon and is secured to the landing-head toward the shore, and the other end rests upon and is secured to the scow carrying the dumping-cars, the bridge only bearing upon the scow carrying it at the middle on the block or superstructure before mentioned. At both ends of the bridge-supporting scow is an upright frame-work over the ends of the bridge, and supporting-levers on each side of the scow, the shorter ends of which levers are connected with the outer ends of the bridge, the length of the le-

vers being parallel with the sides of the bridge, and the inner ends of the levers are provided with balancing-weights, which equal, or nearly equal, the weight of the outer ends of the bridge, to which the outer ends of the levers are connected, so that a slight power applied to the inner ends of the levers will raise the outer ends of the bridge above and away from their connections with the landing-head and the inner end of the car-carrying scow. In this detached state the bridge-carrying scow may (with or without the aid of a tug-boat) be removed to any location desired, to be connected with another landing-head or not, as the case may be; or in case of storm it may be towed to some location where it will be safe from injury. The invention further embraces a landing-head at or approaching the shore, resting upon piles or a wall or other suitable fixed support, with two or more railroad-tracks arranged to correspond with and meet the track on the landing-bridge, but at different heights above the water-level at low tide, so that a locomotive from the shore may be run onto the landing-bridge with safety from one track or the other at any stage of the tide, and, being connected with the train of dumping-cars on the car-carrying scow, will take them on shore with ease, the upward grade from the carrying-scow over the landing-bridge never being high enough to impede the progress of the locomotive with its loaded train of dumping-cars toward the shore, or to render the running of the empty cars from the shore over the landing-bridge to the car-carrying scow in the least hazardous.

The lower track on the landing-head is placed so much above the water-level at low tide that the upward grade from the car-carrying scow over the landing-bridge and landing-head will be about two degrees, the top of the rail-track on the scow and bridge being three to four feet above the water-line. The connection of the landing-bridge with the lower track on the landing-head will be maintained until the water-level is half-way between low and high tide, when the grade off the bridge to the landing will be downward about four degrees, the end of the scow carrying the bridge toward the landing being cut away enough to allow the scow to rise with the tide without coming in contact with the outer end of the bridge to lift it off from its connection with the lower track of the landing-head. When the tide is half-way between low and high the landing-bridge is detached from the lower track and moved sidewise to the point of connection with the upper track, and its landward end raised by means of the levers before mentioned to bring the rails on the bridge to meet those on the landing-head, and the bridge is then secured to the landing-head. This will produce an upward grade from the bridge of about two degrees, which will be gradually diminished as the tide rises, and at high tide the grade off the bridge onto the landing-head will be

again downward about four degrees. The two tracks on the landing-head are run together and united at a distance landward sufficient to make an easy grade from the lower to the upper one.

In the accompanying drawings, in which the parts are indicated by the same letter in the different figures, Figure I is a side view of the landing-bridge and its supporting boat or scow, and a portion of the car-carrying scow connected with the bridge, and a portion of the landing-head, showing one of the tracks on it. Fig. II is an end view of the landing-bridge and its supporting-scow. Fig. III is a diagram, showing the line of the top of the rail-track on the shoreward end of the landing-bridge at the different stages of water—low tide, half-tide, and high tide—and the water-level at low and high tides. Fig. IV is an end view of the landing-head. Fig. V is a side view of the landing-head.

a is the float supporting the landing-bridge. *b* is the car-carrying scow. *cc* is the landing-bridge. *d* is the landing-head. *e* is the connection of the landing-bridge to the landing-head. *f* is the hinged joint connecting the two parts of the landing-bridge. *g* is the supporting-block near the middle of the scow, on which the landing-bridge rests. *h h* is the frame supporting the lever by which the outer ends of the landing-bridge are raised; *i i*, the levers and connections by which the outer ends of the landing-bridge are raised and suspended while the scow and bridge are removed from one location to another; *o o*, the rail-track on the landing-bridge. *d'* in the diagram indicates high-water level. *c'* indicates low-water level; *a'*, top of rail of high landing; *b'*, top of rail of low landing; *c'*, top of rail at middle of landing-bridge when connected with upper landing at half-tide; *m*, top of rail at middle of landing-bridge when connected with lower landing at low tide. *e'* is also top of rail when connected with low landing at half-tide. *n* is top of rail when connected with high landing at high tide.

The diagram Fig. III shows the grade from the middle of the landing-bridge to the landing-head at the different stages of the tide, as before explained.

The landing-head and tracks from it being made ready for use in the usual way of preparing railway-tracks for use in similar situations, either upon piles or masonry, or both, or either, combined with earth-filling and provided with means of bringing up and securing the end of the landing-bridge to it, the landing-bridge and its supporting-scow constructed upon well-known principles of bridge-building and boat-building, and adapted to each other in the manner herein described, with a railway-track upon the bridge and the car-carrying scow, with the railway-tracks above its deck to meet the track on the bridge, and its proper means of connection with the landing-bridge, all substantially constructed,

the bed of the bay or other water and filling up flats or lowlands may be prosecuted much faster and cheaper than it has ever before been done.

The steam-dredger may be located and from time to time moved as the material within its reach is all taken up. A suitable tug-boat tows the car-carrying scow with its train of dumping-cars on board to the dredger, by which the dumping-cars are quickly filled. The tug-boat then proceeds with the scow and cars to the landing-bridge, to which the scow is secured. The locomotive is then backed down onto the landing-bridge attached to the dumping-cars, and steams away with them to the place where the filling is wanted, dumps the contents, and returns the cars again on board of the scow, to be again towed to the dredge and refilled, and so on until the work is completed.

It is obvious that two trains of dumping-cars may be used, thus keeping the tug, dredger, and locomotive, and the persons attending them more fully employed.

The saving of cost of filling low lands and flats near the water by the means here de-

scribed will be very important, and notably so, as the work can be continued without interruption at all stages of the tide, and, if desirable, night as well as day time.

With slight modification this system could be used with great advantage in transferring trains of passenger or freight cars across rivers and arms of the sea where the tide flows.

I claim as new—

1. In combination, a car-carrying scow, a floating portable landing-bridge, and a landing-head with tracks at different heights, all constructed and arranged substantially as described, and for the purpose specified.

2. A portable floating landing-bridge consisting of a supporting-float and a bridge in two parts, hinged upon a supporting-block at the middle of the float, and the outer ends suspended from movable balanced levers, all constructed and arranged substantially as described, and for the purpose specified.

ALBERT E. HALL.
